DIRECT COUPLED AMPLIFIER

John R. Beckwith, Chicago, Ill., assignor, by
mesne assignments, to Belmont Radio Corpora-
tion, Chicago, Ill., a corporation of Illinois

Application June 12, 1944, Serial No. 539,933

5 Claims. (Cl. 179—171)

This invention relates to direct-coupled amplifiers and more particularly to such amplifiers of the type by means of which substantially linear, distortionless and quiet amplification may be obtained.

There are many applications in the art for multi-stage direct-coupled amplifiers; that is, amplifiers having a uniform response to all frequencies down to zero frequency or direct current. Such amplifiers are to be distinguished from those employing inductive, capacitive, or mutual inductive or transformer couplings between the successive stages, all of which coupling elements have non-uniform frequency-response characteristics and the latter two of which do not translate direct-current signals.

Heretofore there have been proposed various direct-coupled amplifiers certain of which have involved operation of the successive stages of the amplifier at progressively higher cathode and anode potentials in order to maintain proper grid biases on the tubes of the several stages. This arrangement, however, involves several well-known disadvantages such as increased shock hazards, the occurrence of spurious signals which are induced in the stages operating substantially above ground potential, and the uneconomic use of the power supply. Other direct-coupled amplifier circuits heretofore proposed have involved the more or less complicated networks to avoid the disadvantages of the circuit arrangement described, but have resulted in a signal output which was distorted or noisy or both.

It is an object of the invention, therefore, to provide a new and improved direct-coupled amplifier by means of which one or more of the above-mentioned disadvantages of the prior art arrangements may be overcome.

It is another object of the invention to provide a new and improved direct-coupled amplifier in which the successive stages are not operated at progressively higher potentials and in which the overall amplification of each stage is substantially linear, distortionless and quiet.

In accordance with the invention, there is provided in a multi-stage direct-coupled amplifier a substantially linear amplifier stage comprising a vacuum tube amplifier having a signal input circuit and an anode load circuit including an anode load impedance. The stage also includes a vacuum tube repeater having a control electrode circuit and a cathode circuit including a cathode load impedance, the control electrode circuit including a portion of the cathode load impedance. The stage also includes

a circuit for impressing anode voltage fluctuations of the amplifier upon the anode of the repeater and a signal output circuit directly coupled to the cathode load impedance and adapted for connection directly to a succeeding amplifier stage.

For a better understanding of the invention, together with other and further objects thereof, reference is had to the following description taken in connection with the accompanying drawing while its scope will be pointed out in the appended claims.

Referring to the single figure of the drawing, there is represented schematically a circuit diagram of a two-stage direct-coupled amplifier embodying the invention.

Referring now to the drawing, the multi-stage direct-coupled amplifier there represented comprises a substantially linear first amplifier stage 10 coupled to a second amplifier stage 11. The first amplifier stage 10 comprises a vacuum tube amplifier 12 having a signal-input circuit connected to input terminals 13 across which is connected a grid leak resistor 14. The tube 12 is provided with a self-biasing cathode circuit comprising a resistor 15 and a by-pass condenser 16. The tube 12 also has an anode load circuit including an anode load impedance, such as a resistor 17, connected between its anode and a source of space current, indicated as +B. The amplifier stage 10 also includes a vacuum tube repeater 18 having a cathode circuit including a cathode load impedance consisting of resistors 19 and 20 in series. The tube 18 is also provided with a control electrode circuit, for example, its control electrode is connected to a point on the cathode load impedance, such as the junction of the resistors 19 and 20. The stage 10 also includes a circuit for impressing the anode voltage fluctuations of the vacuum tube amplifier 12 upon the anode of the repeater 18. For example, the repeater 18 may be connected directly in parallel with the amplifier tube 12, as indicated. The stage also includes a signal-output circuit including terminals 21 directly coupled across the cathode load impedance consisting of resistors 19 and 20; this signal-output circuit, as explained hereinafter, being adapted for connection directly to the succeeding amplifier stage 11. The amplifier tube 12 may be of any suitable type, there being illustrated by way of example a screen-grid tube the screen electrode of which is connected to the terminal +B through a dropping resistor 22 and is by-passed 55 for signal-frequency currents by a condenser 23.

The second amplifier stage 11 is shown as comprising a conventional screen grid amplifier tube 24 connected to the source +B through an anode load resistor 25 and provided with a cathode bias resistor 26 by-passed by condenser 27. The bias on the cathode of the tube 24 is determined by means of a voltage divider comprising a resistor 28 and the resistor 26 connected in series across the source +B. The tube 24 is illustrated as also being of the screen grid type, its screen electrode being connected to the source +B through a dropping resistor 29 and being by-passed to ground for signal-frequency currents by means of a condenser 30. The output circuit of the amplifier stage 11 includes the terminals 31 connected across the anode load resistor 25 of vacuum tube 24, as indicated.

In the operation of the direct-coupled amplifier system described, the vacuum tube 12 and its associated circuit elements operates in a conventional manner to amplify the signal applied to the input terminals 13. The amplified signal output appears at the anode of the tube 12 and this signal is applied directly to the anode of the vacuum tube repeater 18. The connection of the control electrode of the tube 18 to the junction of the resistors 19 and 20 serves two purposes: first, the resistor 19 provides an appropriate bias to the control electrode of tube 18, and second, since the resistor 19 is not by-passed, the connection of the control electrode of tube 18 is effectively a degenerative one which imparts to the tube 18 a non-linear resistance characteristic. Specifically, increases in the anode potential of the tube 18 effectively increase the space current through the tube and the cathode load resistors 19 and 20, thus increasing the negative instantaneous bias on the grid of the tube 18 and increasing its effective resistance. As a result, the current fluctuations through this circuit are partially degenerated and the signal voltage appearing across the cathode load circuit 19, 20 is correspondingly degenerated.

It is well-known that all vacuum tube amplifiers, such as the amplifier 12, have a certain amount of curvature in their mutual conductance characteristic, that is, they are not entirely linear amplifiers. By virtue of the degenerative connection of the control electrode of tube 18, its resistance fluctuations are substantially out of phase with the variations in the mutual conductance of the tube 12 so that it is effective at least in part to compensate for the non-linearity of the tube 12. By a proper selection of the values of resistors 19 and 20, this compensation of non-linearity may be made very nearly exact.

The signal output of the stage 10 appearing at the terminals 21 is a uni-directional signal having an average positive value, but still one of low enough value that it may be applied directly to the control electrode of the amplifier tube 24 of stage 11. Nevertheless, in order to insure a proper operating bias on the control electrode of this tube, its cathode is biased positively by means of the voltage divider comprising resistors 28 and 26 in series across the source +B. The amplifier stage 11 operates in a conventional manner to supply to its output terminals 31 an amplified undistorted reproduction of the signal input applied to the terminals 13 of stage 10.

While the invention has been illustrated as embodied in a two-stage direct-coupled amplifier, it will be understood that any desired number of amplifier stages similar to the stage 10 may be connected in cascade. However, it is preferable

that the final amplifier stage be a conventional one, as represented by the stage 11, since the portion of the stage 10 including the repeater 18 actually attenuates the signal so that the gain of stage 10 is less than that of a stage of the type of stage 11.

It will be apparent that the circuit constants of the direct-coupled amplifier system represented in the drawing may be selected in accordance with the design requirements of any particular installation. By way of example, however, the following are given as representative of a particular amplifier stage:

15	Tube 12	-----	Type 6V6
	Tube 18	-----	Type 6SN7 (one space-current path)
	Tube 24	-----	Type 6L6
10	Resistor 19	-----	820 ohms
	Resistor 20	-----	10,000 ohms
15	Resistor 17	-----	18,000 ohms

In a direct-coupled amplifier embodying the circuit constants given above, the repeater tube 18 was determined to provide an amplification factor of 0.35.

20 25 While there has been described what is at present considered to be the preferred embodiment of the invention, it will be apparent to those skilled in the art that various changes and modifications may be made therein without departing from the spirit or scope of the invention.

What is claimed as new is:

1. In a multi-stage direct-coupled amplifier, a substantially linear amplifier stage comprising, a vacuum tube amplifier having a signal-input circuit and an anode load circuit including an anode load impedance, a vacuum tube repeater having a control electrode circuit and a cathode circuit including a cathode load impedance, said control electrode circuit including a portion of 30 said cathode load impedance, a circuit for impressing anode-voltage fluctuations of said amplifier upon the anode of said repeater, and a signal-output circuit directly coupled to said cathode load impedance and adapted for connection directly to a succeeding amplifier stage.

2. In a multi-stage direct-coupled amplifier, a substantially linear amplifier stage comprising, a vacuum tube amplifier having a signal-input circuit and an anode load circuit including an anode load impedance, a vacuum tube repeater connected in parallel with said vacuum tube amplifier and having a control electrode circuit and a cathode circuit including a cathode load impedance, said control electrode circuit including a portion of 40 said cathode load impedance, and signal-output circuit directly coupled to said cathode load impedance and adapted for connection directly to a succeeding amplifier stage.

3. In a multi-stage direct-coupled amplifier, a substantially linear amplifier stage comprising, a vacuum tube amplifier having a signal-input circuit and an anode load circuit including an anode load impedance, a vacuum tube repeater having a control electrode and a cathode circuit including a cathode load impedance, said control electrode circuit including a cathode load impedance, a connection from a point on 50 said cathode load impedance to said control electrode, a circuit for impressing anode-voltage fluctuations of said amplifier upon the anode of said repeater, and a signal-output circuit directly coupled to said cathode load impedance and adapted for connection directly to a succeeding amplifier stage.

4. In a multi-stage direct-coupled amplifier comprising, a substantially linear first amplifier 60 circuit including a cathode load impedance, a connection from a point on said cathode load impedance to said control electrode, a circuit for impressing anode-voltage fluctuations of said amplifier upon the anode of said repeater, and a signal-output circuit directly coupled to said cathode load impedance and adapted for connection directly to a succeeding amplifier stage.

5. A multi-stage direct-coupled amplifier comprising, a substantially linear first amplifier 65 circuit including a vacuum tube amplifier having

a signal-input circuit and an anode load circuit including an anode load impedance, a vacuum tube repeater having a control electrode circuit and a cathode circuit including a cathode load impedance, said control electrode circuit including a portion of said cathode load impedance, a circuit for impressing anode-voltage fluctuations of said amplifier upon the anode of said repeater, and a second amplifier stage coupled directly to said cathode load impedance.

5. In a multi-stage direct-coupled amplifier, a substantially linear amplifier stage comprising, a vacuum tube amplifier having a signal-input

circuit and an anode load circuit including an anode load resistor, a vacuum tube repeater having a control electrode circuit and a cathode circuit including a cathode load resistor, said control electrode circuit including a portion of said cathode load resistor, a circuit for impressing anode-voltage fluctuations of said amplifier upon the anode of said repeater, and a signal-output circuit directly coupled to said cathode load resistor and adapted for connection directly to a succeeding amplifier stage.
